TIRE

Bernard E. Mendelsohn, Brookline, Mass., assignor of one-half to B. Howard Benson, Boston, Mass.

Application September 9, 1941, Serial No. 410,183

1 Claim. (Cl. 152—339)

The present invention relates to tire construction, and in particular to safety tires for use on motor vehicles for both air-crafts and ground machines.

The present invention has for its object the over-comeing of certain difficulties which constructions of the prior art have been troubled with.

In all vehicles, and particularly in vehicles which bear heavy loads or which are intended to be driven at high speeds, the stresses on the rubber shoes at times becomes very great. This is particularly true with air craft wheels, which while in use only for very short distances, such as taking off or landing, never-the-less must endure great stresses at such times, first because of the load of the machine, and secondly, because taking off and landing speeds are often considerably higher than that of the driving speed of the ordinary automobile. In addition to this, forced landing and imperfect landings are such as to stress unduly the rubber shoes of the wheels. Automobile and air-craft shoes are made with varying ply cords running up as high or higher than thirty-six plies in order to be strong enough to with-stand bursting stresses which occur in their use.

The present invention relates to a safety shoe in connection with such constructions. The applicant has previously used a shoe in which an air chamber is formed between the shoe itself and internal flexible but non-yielding fabric partition which is anchored about the bead of the shoe. This partition, because of the manner in which it is held to the shoe, permits a fairly complete deformation of the shoe, for instance when the machine hits a bump or comes down heavily, without putting too great a stress upon the partition itself. However, in some cases the construction cannot be such as to allow sufficient deformation to prevent undue stresses upon the fabric partition.

In the present invention abnormal deformations are prevented without unduly stressing the partition. This is accomplished principally by adding in the top central section in the fabric partition, a yielding flexible section yielding under excessive pressures so that the fabric in the partition will not be unduly strained. In this case the fabric portions of the partitions may be formed and molded with the ply layers of the shoe with their inner edges free, permitting the addition of the yielding section after the shoe has been substantially completed. In this construction the inner fabric partition strengthens and

reinforces the shoe about the bead by the addition of the number of layers of fabric used in the partition itself. This method and construction may be employed with a number of modifications. 5 Within the inner partition is the usual inflation tube which may be joined with the chamber through a release valve which releases under the desired pressure.

Various other and further modifications may 10 be employed within the principles of the invention as generally described above, but in its preferred form the invention is described below in connection with the specification and drawing illustrated showing an embodiment of the same, in 15 which:

The sole figure shows a radial section through the shoe and the rim.

Referring to the figure, 1 represents the shoe which may be built up of any number of plies, 20 depending upon the use to which the shoe is to be put. On the inner surface of the shoe 1, a non-leak seal compound 2 of rubber or other suitable material may be used. The purpose of this is to prevent the air from escaping through the shoe from the chamber 3. The inner wall of the chamber 3 is formed by the partition 4 which comprises layers of fabrics 5 and rubber 6 in its side walls which is non-extensible but flexible and a top portion 7 of pure rubber which is 25 mounted or joined at its sides 8 and 9 to the side fabrics 5. The side fabrics 5 forming the sides of the inner partition are preferably molded as a part of the shoe in the formation of the shoe. This may be done by moulding and curing the 30 side fabrics 5 with the fabrics 10 and 10 forming the sides of the shoe, some suitable material being placed between the fabrics 5 and 10 to prevent the former from adhering to the side walls of the shoe. The fabrics 5 in this way have their 35 other ends molded or formed as an integral part of the shoe itself, extending in the form of a flap or apron from the bead 11 of the shoe when the shoe is made. The section around the base is 40 here referred to as the bead section.

45 The yielding portion 7 of the inner partition may then be vulcanized or molded to the free edges of the flaps all the way around the shoe, thus completing the formation of the partition. The extensible rubber piece 7 should be of considerable thickness in comparison to the inner tube 12 which rests against the inner partition at its inner side. The purpose of this is to permit considerable pressure to be built up within the chamber 13 formed by the inner tube 12 before the rubber top member 7 will expand. Ordin-

nearly fifteen pounds per square inch pressure is desirable within the chamber 13 before the member 7 will expand. In this way the tube 7 will be provided with a greater pressure than the pressure in the external chamber 3. The member 7 is preferably positioned at the top of the partition and is intended to permit an extensibility of the member 7 of approximately 100%, so that with 100% stretch in the member 7, the inner chamber 13 will be expanded to fill the whole shoe.

This provision eliminates excessive stresses in the side fabrics, since in the present construction when the member 7 stretches, the side fabrics 5 move outward with the bead as the anchor point until the fabrics 5 come in contact with the inner wall of the shoe. The differential pressure between the inner chamber 13 and the outer chamber 3 is obtained by means of the connecting valve 14 between the tube 12 and the external chamber 3. This valve may be of a known construction and comprises a valve stem 15 at the end of which is a piston 16 which sits against the valve seat 17. A spring 18 exerts a pressure between the inside of the valve seat 17 and a head 18 formed at the end of the valve stem in such a way that the piston 16 will not be raised from its seat to permit the air to escape from the chamber 13 to the chamber 3 until the desired pressure, for instance fifteen pounds per square inch is a differential between the two chambers.

The valve may be installed by cementing to the fabric of the side walls, a disc 19 having a bushing 20 into which is inserted the collar element 21 which extends from the disc 22 cemented to the outside wall of the inner tube 12. The chamber 13 may be inflated by the valve 23 in the usual manner and as the pressure in the chamber 13 becomes sufficiently great so that the valve 14 opens, the external chamber becomes inflated. The valve is adjusted so that it will open at a pressure less than that required to

expand the rubber element 7 to any great degree so that air begins to flow into the external chamber 3 before any appreciable expansion of the internal chamber occurs, and in this manner the desired ratio of chamber size between the inner and outer chamber is maintained.

If a blow-out should occur, initially the inner chamber will expand and fill out the entire space within the shoe. Subsequent to this air would escape from the inner chamber until its pressure was equal to the established pressure differential in which case the inner chamber would come back to its general normal size and the machine would be run under these conditions maintaining partial pressure on the tires.

The present arrangement also permits ready repair of the external chamber in event that a puncture occurs through the shoe wall. In this case the rubber wall of the internal partition at 7 may be slit and the leak readily repaired if the repairs cannot be made from the external side. If the rubber partition 7 is slit a new piece of rubber may be vulcanized or cemented to the piece 7 in the same manner that an inner tube might be repaired. The rubber member 7 should of course be made of such a thickness that a stretch of the nature required, that is, approximately 100% will not be of such a nature as to decrease the thickness of the member beyond the point where the stress is greater than that permissible under working conditions.

Having now described my invention, I claim:

A pneumatic tire casing for motor vehicles and the like comprising an outer shell of rubber and fabric adapted to fit on the rim of a wheel and having beads adapted to be in contact with said rim, an inner casing having fabric side walls cured to said outer casing in said beads and an extensible yielding rubber piece forming the crown wall of said inner casing and joined at both sides to said fabric side walls.

BERNARD E. MENDELSON.
